UNITED STATES PATENT OFFICE

WILLIAM E. WATKINS, OF NEW YORK, N. Y., ASSIGNOR TO COPPER PLATE SHEET & TUBE COMPANY, OF NEW YORK, N. Y., A CORPORATION OF NEW JERSEY

APPARATUS FOR HANDLING SHEET METAL

Application filed September 6, 1929. Serial No. 390,787.

This invention relates to apparatus for handling sheet metal, and more particularly to means for flattening or decrowning arched metal sheets. This application is a continuation, in part, of my copending application, Serial No. 116,486, filed June 16, 1926.

In the said application I have disclosed a complete process of treating sheet metal and apparatus therefor in which the sheets are arched and pickled, then decrowned or flattened, dried, cold rolled, coated, if desired, with a film of oil, again arched, then annealed while in arched form, again pickled and washed, and then passed through a straightening apparatus.

The present application is directed to the decrowning or flattening apparatus by means of which the arched sheets are flattened. In my copending application the decrowning mechanism consists of two converging sets of rollers between which the arched sheets are fed. In the present invention, I employ conveyors consisting of strips connected to parallel endless conveyor chains, and two of the conveyors are arranged in converging planes in the manner disclosed in my earlier applications.

In the drawings, Fig. 1 is a longitudinal, sectional view of the decrowning mechanism arranged at the outlet end of an annealing furnace;

Fig. 2 is a plan view, parts being shown in section;

Fig. 3 is a vertical, transverse, sectional view on line 3—3 of Fig. 1;

Fig. 4 is a plan view of one of the transverse strips of the conveyor; and

Fig. 5 is a front elevation thereof.

The drawings illustrate a delivery casing 1 arranged at the outlet end of the annealing furnace disclosed and claimed in my copending application referred to above. This casing encloses an auxiliary conveyor 2 which serves to pick up the sheets from the furnace conveyor 3 and deliver them to the decrowning mechanism forming the subject matter of this application. The delivery chamber 1 and the decrowning mechanism are all in open communication with the furnace chamber. The decrowning mechanism is arranged

in a chamber or casing 4 and comprises two endless conveyors 5 and 6 arranged to converge at the rear end of the decrowning mechanism. The sheets are carried forward by the lower conveyor 6 and are spread out flat as they come in contact with the upper conveyor 5. The conveyors consist of chains 7 passing over suitable sprockets. The lower conveyor passes over sprockets 8 and 9 mounted on shafts 10 and 11, respectively, adjacent the opposite ends of the casing and the upper conveyor passes over sprockets 12 and 13 mounted on shafts 14 and 15, respectively. The pair of chains forming each conveyor are connected by cross strips 16 which are riveted to the links of the conveyor chain as indicated at 17 in Fig. 4 of the drawings. The lower conveyor is provided with suitable means to prevent lateral movement of the sheets. As shown, I provide a lug 18 adjacent each side of each of the lateral strips 16 and these lugs project upwardly and engage the edge of the sheet to prevent lateral movement of the sheet, if the sheet moves toward the side of the conveyor. Instead of placing the lugs on each of the lateral strips, they may be spaced at suitable intervals so that there will always be a lug in position to engage a portion of the edge of the sheet if the sheet moves laterally. The flattening device 80 may be driven in any suitable manner. As shown (see Fig. 3) a sprocket 19 is arranged on the shaft 11 and a chain 20 passes over this sprocket. The chain is connected to any suitable source of power (not shown). The opposite end of this shaft also carries a sprocket adapted to receive a chain 21 passing over a sprocket on the adjacent shaft 15 of the upper conveyor.

The operation of the device will be apparent from the foregoing description. The arched sheet is fed forwardly on the lower conveyor 6 and its arched surface is engaged by the upper converging conveyor 5. As the sheet approaches the rear end of the casing, it is flattened by the convergence of the two conveyors and after it leaves the conveyors it passes through suitable straightening rollers 22 which may be driven in any suitable manner.

I claim:

1. A sheet flattening device for flattening arched metal sheets comprising a pair of converging planes to flatten the sheets as they advance through the device, each of said conveyors comprising a pair of side chains spaced apart a distance greater than the width of the sheet, transverse strips connecting said chains, and means for driving one of said conveyors to advance the sheet.
2. A sheet flattening device for flattening arched sheets comprising an endless conveyor consisting of a pair of side chains spaced apart a distance greater than the width of the sheet and transverse strips connecting said chains, a second conveyor arranged over said first conveyor and comprising a pair of side chains and transverse strips connecting said side chains, the lower flight of said second conveyor converging toward the upper flight of said first conveyor and being adapted to engage the arched central portion of a sheet traveling on said first conveyor, and means carried by the transverse strips of said first conveyor to prevent lateral movement of the sheets.
3. A sheet flattening device for flattening arched sheets comprising an endless conveyor consisting of a pair of side chains spaced apart a distance greater than the width of the sheet and transverse strips connecting said side chains, a second conveyor arranged over said first conveyor and comprising a pair of side chains and transverse strips connecting said side chains, the lower flight of said second conveyor converging toward the upper flight of said first conveyor and being adapted to engage the arched central portion of a sheet traveling on said first conveyor, and lugs carried by the transverse strips of the first conveyor to restrict the lateral movement of the sheets.

In testimony whereof I affix my signature.
